CLAIM

The ornamental design for a extension handle for a track switch tool, as shown and described.

DESCRIPTION

FIG. 1 is a front, left side and top perspective view of an extension handle for a track switch tool showing my new design;

FIG. 2 is a front elevational view thereof;

FIG. 3 is a rear elevational view thereof;

FIG. 4 is a top plan view thereof;

FIG. 5 is a left side view thereof, the right side being a mirror image; and,

FIG. 6 is a bottom plan view thereof.

The broken line showing of a railroad switch arm and a retainer pin in FIG. 1 is for illustrative purposes only and forms no part of the claimed design.
